 ROTHGERBER CHRISTIE LLP(57) **CLAIM**

The ornamental design for tobacco bowl, as shown and described.

DESCRIPTION

FIG. 1 is a perspective view of a tobacco bowl design;
 FIG. 2 is a front view thereof;
 FIG. 3 is a right-side view thereof;
 FIG. 4 is a rear view thereof;
 FIG. 5 is a left side view which is the mirror image of the right side view thereof;
 FIG. 6 is a top view thereof; and,
 FIG. 7 is a bottom view thereof.
 The broken lines in the drawings are for illustrative purpose only and form no part of the claimed design.
